CUSHIONED CAR RAIL

Curt Saurer, Akron, Ohio, assignor to The Firestone Tire & Rubber Company, Akron, Ohio, a corporation of Ohio

Application June 4, 1931, Serial No. 541,962

1 Claim. (Cl. 238—9)

This invention relates to railways, and more especially it relates to railways comprising car rails which are yieldingly mounted in concrete or other non-yielding road-building material.

5 All car rails are subject to vibration induced by the passage of cars and other vehicles thereover, and when the rails are embedded in concrete or similar material, such vibration quickly effects separation of the rail and concrete and 10 eventually damages the foundation structure of the rails, the destructive action of the vibration being expedited by moisture which enters the space between the rails and the concrete after their initial separation. Attempts to remedy the 15 situation, so far as I am aware, consist in mounting shock absorbing fibre blocks between rails and ties, and while this expedient protects the foundation structure from rail vibration, it does not prevent the head or flange of the rails from 20 damaging the adjacent concrete, and does not prevent the entrance of moisture.

The chief objects of this invention are to prevent damage to the foundation structure of a railway from rail vibration; to prevent damage 25 to adjacent concrete or brick from vibration of the head and/or flange of the rails; to reduce the noise incidental to car travel on the rails; and to prevent the entrance of moisture between the rails and adjacent pavement.

30 The single figure of the accompanying drawing is a transverse section through one rail of a railway embodying the invention in its preferred form.

Referring to the drawing, 10 is track rail, and 35 is shown herein as a rail of the type comprising a head 11 formed with a lateral flange 12, the rail also having the usual base portion 13. Mounted upon the under side of the head 11 and flange 12 of the rail are respective cushions 14, 40 14 of resilient rubber composition, said cushions extending longitudinally the full length of the rail. The cushions 14 either are vulcanized to the rail, or are adhesively attached thereto after initially being vulcanized in extruded or molded 45 form. The bottom face of the base portion 13 of the rail is provided with a resilient rubber cushion 15 which may consist of a single strip extending the full length of the rail, or it may consist of a plurality of short strips that are 50 spaced apart so as to underlie only those portions of the rail that rest upon ties, such as the metal

tie 16. The cushion or cushions 15 are applied to the rail in the same manner as the cushions 14. Suitable bolts 17 are provided for securing the rail 10 to the tie 16, which bolts extend through suitable apertures formed in the tie 16, cushion 15, and rail base 13, and are provided respectively with washers 18 having non-parallel faces, and nuts 19 for urging said washers against the top face of the rail base 13.

The railway consisting of parallel rails of the 10 construction and mounting described, when laid in a paved roadway is substantially embedded in the paving material such as the concrete 20, only the top of the rail head 11 and flange 12 being exposed. In pouring the concrete, narrow spaces 15 are left along the lateral faces of the said head and flange, and these spaces subsequently are filled with a composition of asphalt, pitch or rubber that adheres to the rail and to the concrete and provides seals 21, 21 to prevent the 20 entrance of moisture between the rail and pavement.

Preferably the seals 21 are of such composition and consistency as to remain permanently flexible, that is, never to crack or fracture under the 25 rail-vibration to which they are subjected.

When the trackway is initially constructed, the concrete adheres to the rails, but after a relatively short interval of use, due to vibration of the rails, this adhesion fails and a crack 30 is formed between the metal and the concrete. Thereafter vibration of the rails is absorbed by the rubber cushions 14, 15 and further damage to the pavement or rail-supporting structure is 35 obviated.

Modification may be resorted to within the scope of the appended claim which is not limited wholly to the specific construction shown and described.

40 What is claimed is:

In a railway, the combination of ties, track rails, rubber cushions between the ties and track rails, rubber cushions on the under side of the heads of the rails, and rigid paving material in contact with the sides of the rails and with the aforesaid members in which the paving material is flush with the top surface of the rails, including non-frangible water seals between the lateral faces of the rail heads and the adjacent pavement structure.

50 CURT SAURER.
